UNITED STATES PATENT OFFICE.

FREDERICK S. BURNHAM, OF WELLESLEY, MASSACHUSETTS.

APPARATUS FOR WASHING AND STERILIZING BOTTLES.

1,400,797.

Specification of Letters Patent. Patented Dec. 20, 1921.

Application filed December 19, 1916. Serial No. 137,863.

To all whom it may concern:

Be it known that I, FREDERICK S. BURNHAM, a citizen of the United States of America, and a resident of Wellesley, Massachusetts, have invented a new and useful Improvement in Apparatus for Washing and Sterilizing Bottles, which invention is fully set forth in the following specification.

This invention relates to apparatus for 10 washing or sterilizing articles and, while capable of use for so treating a wide variety of articles, is especially adapted to the washing or sterilizing of bottles.

An object of this invention is to provide 15 a device of the type described whereby, without especial skill, a relatively large number of articles to be cleansed, as bottles, may be assembled as a unit and as a unit positioned in operative relation to distributing means for the washing or sterilizing fluid.

A further object of this invention is to provide a device of the character described, wherein the distributing means for the 25 washing or sterilizing fluid comprises a plurality of nozzles or nipples adjustably mounted whereby the spacing of said nozzles or nipples may be varied in accordance with the size of the articles to be cleansed. Still a further object is to provide in connection with adjustably mounted nozzles or nipples as last referred to, means whereby the spacing of said nozzles or nipples may be simultaneously and proportionately varied.

Further objects relate to the provision of 35 a washing or sterilizing apparatus having a cover provided with distributing means for a washing or sterilizing fluid, which distributing means is brought into operative relation with the articles to be cleansed by the closing of the cover; having means, as a calibrated device, for the ready predetermining of the spacing of the nozzles; and having adjustable means for predetermining 45 the position of the portable device by which the articles to be cleansed are positioned in operative relation to the distributing means for the washing or sterilizing fluid.

Yet other objects relate to the provision 50 of a device of the type described that shall be simple in construction, easily assembled, inexpensive to manufacture, and efficient in use.

Stated broadly, the washing or sterilizing 55 apparatus comprises a container, preferably provided with a cover, distributing means

for a washing or sterilizing fluid within said container, and portable means wherein may be assembled a plurality of articles to be cleansed and by which said articles may be 60 positioned in operative relation to the distributing means for the washing or sterilizing fluid. Said distributing means preferably comprises a plurality of nozzles, said nozzles being maintained in spaced relation- 65 ship by adjustable means enabling their spacing to be simultaneously and proportionately varied. The cover of said container is also preferably provided with distributing means for a washing or sterilizing 70 fluid, such distributing means being brought into operative relation with the articles to be cleansed by the closing of said cover.

The invention is capable of receiving a variety of mechanical expressions, one of 75 which is shown on the accompanying drawings. It is to be expressly understood that the drawings are for purposes of illustration only, and are not to be construed as definitions of the limits of the invention, reference 80 being had to the appended claims for that purpose.

In the drawings, wherein the same reference characters designate corresponding parts in the several figures,

Fig. 1 is a perspective view of the container showing the nozzles therein;

Fig. 2 is a perspective view of the portable means for assembling the articles to be cleansed, showing the two parts thereof in 90 separated relationship.

Fig. 3 is an enlarged longitudinal vertical section through the container;

Fig. 4 is an enlarged horizontal section through the container;

Fig. 5 is an enlarged transverse vertical section through the container;

Fig. 6 is an enlarged horizontal section through the container upon a different scale and showing the adjusting members for the 100 nozzles provided with means to maintain their parallelism; and

Fig. 7 is a detail upon a still larger scale of one of the nozzles.

While the invention is illustrated as applied to the washing or sterilizing of bottles, it is to be expressly understood that the same is not restricted to this use, as other uses will readily suggest themselves to those skilled in the art.

Referring in detail to the drawings, 1 is a container of any suitable shape, and 2 is a

cover therefor preferably hinged thereto as shown in Fig. 1.

Within the container are distributing means for a washing or sterilizing fluid, said means preferably comprising a plurality of individually movable nozzles 3 of which any suitable number may be employed and which are arranged in rows. Each of said nozzles 3 is connected by a flexible conduit, 10 as a piece of rubber-tubing 4, with one of a plurality of pipes 5, shown as positioned in the bottom of the container, said pipes 5 communicating adjacent one end with a header 6 from which extends suitable piping 15 7 provided with a valve or valves 8 by which a suitable washing or sterilizing fluid or fluids, such as steam, alkaline solution, or pure water, may be at will admitted to said header 6, and thereby through the pipes 5 20 and conduits 4 to the nozzles 3.

Means, preferably adjustable, are provided for maintaining the nozzles 3 in spaced relationship. As shown, each of the four sides of the container is provided with a 25 ledge 9, and upon the opposed pairs of ledges are supported two sets of transverse members 10. Each of said members is shown as provided with a longitudinal slot extending throughout the major portion thereof. Said members may be constructed in a variety of ways, the illustrated form comprising a bar slotted longitudinally as described. At each point of intersection of each member with a member extending at right-angles 35 thereto is positioned a nozzle, said nozzle extending through the slots of both said members and being provided with a collar 11 between said members, whereby the nozzle is retained in position. The members of 40 each of said sets are preferably in parallel relation, this parallelism being maintained by suitable means, as links, as illustrated in detail in Fig. 6. As here shown, one member of each set, preferably the central member, is maintained fixedly in position, as by 45 screws 12 passing therethrough into the corresponding ledges, and a lazy-tongs, one at each end of each of said sets, is operatively connected with all the said members 50 of the corresponding set. The outer pivot of each link of a lazy-tongs is mounted on one of the members 10 at 13, and the inner pivot of each link comprises a pin 14 working in the slot of an adjacent member 10. 55 Thereby the members of each set are maintained in parallelism, while the members of either set may be moved to vary the distance between said members, the movement of one set being transmitted to the nozzles which 60 are guided in their movement by the members of the other set. Accordingly, the relative spacing of all the nozzles will be simultaneously and proportionately varied by the movement of any one member of either set.

Means are preferably provided for pre-

determining the spacing of the aforesaid parallel members and therefore of the nozzles, such means taking any suitable form. As shown, calibrated bars 15 are positioned above the aforesaid members and attached to 70 the ledges 9 in any suitable way, as by clamping screws 16. Said calibrated bars 15 may also exert a clamping action upon the members of the respective transverse sets whereby to maintain the same fixedly in position 75 after adjustment.

The cover 2 of the container may also be desirably provided with distributing means for the washing or sterilizing fluid. As shown, said cover carries in any suitable way 80 a plurality of pipes 17 provided with apertures whereby the same constitute a spraying apparatus. Said pipes are connected with an inlet pipe 18 provided with a valve 19, said pipe 18 being connected with the 85 source of fluid by a flexible connection, as a piece of rubber-tubing 20, whereby the cover may be opened and closed with respect to the body of the container 1. The cover may also desirably be provided with a sealing strip 90 21 suitably attached to an extending ledge 22 provided thereon, said sealing strip engaging a ledge 23 provided on the upper edge of the body of the container. If desired, clamping devices 24 may be permanently pivoted to the body of the container and be provided with clamping screws 25 adapted to engage the aforesaid ledge 22 when swung upwardly into position above the same.

For assembling a plurality of the articles to be cleansed, a portable device of the type shown in Fig. 2 is provided. As shown, this portable device comprises a receptacle 26 of suitable size and shape to snugly hold 105 a definite number of the articles to be cleansed. A second part 27 comprises a frame adapted to fit upon the upper edge of receptacle 26, said frame being provided with a plurality of longitudinal bars or 110 rods 28 adapted to engage the articles in the receptacle 26 and retain and support the same in position when the portable device is inverted. When such articles are bottles, the rods or bars 28 are so spaced 115 as to receive the necks of the bottles between them, but to engage the shoulders of the bottles and constitute supporting means therefor when inverted in operative relation to the nozzles 3.

Means are preferably provided for predeterminedly the position of the portable device, when the same is used to operatively position the articles to be cleansed with respect to the nozzles. Any suitable means of 125 this type may be employed. As shown, each of two opposing ledges 9 is provided with a plurality of holes 29, and a bar 30 is provided at each end with a pin 31 to engage in any one of the holes in the corresponding 130

ledge. Mounted upon bar 30 is a pair of sleeves 32, each provided with an upstanding flange 33 shaped to engage the extremities, as the corners, of the portable device 5 heretofore described. The sleeves 32 are slideable upon the rod 30, and to retain the same in adjusted position each is provided with any suitable means, as a spring-pressed clamping pin 34.

10 Assuming the articles to be cleansed to be bottles of various sizes, the bottles are as sorted in accordance with their size, and a receptacle 26 selected in which may be assembled in snug relationship a relatively 15 large number of bottles of a definite size. Frame 27 is next mounted upon the receptacle 26 with the necks of the bottles protruding between the bars or rods 28. Members 10 are then so spaced that the nozzles 20 have equal spacing with the necks of the bottles. Receptacle 26 with its frame 27 is now inverted and positioned with the bottles in operative relation to the nozzles 3, as shown in Figs. 3 and 5, wherein the frame 25 27 is shown in full lines and the receptacle 26 in dot-and-dash lines. When the positioning device as shown in Fig. 4 is employed, bar 30 is moved to engage its pins 31 with the proper apertures 29, and sleeves 32 are 30 slid along said bar until the upstanding flanges 33 engage the corners of the frame 27. Receptacle 26 may then be removed, the bottles being supported by the engagement of bars or rods 28 with the shoulders there- 35 on, as clearly shown in Fig. 5, the frame 27 resting upon the members 10 which thereby constitute a support for the bottles in operative relation to the nozzles 3 which, as shown, then extend into the interiors of the 40 bottles. Cover 2 may then be closed, clamping devices 24, when used, being swung up and screws 25 engaged with flange 22. Strip 21 then seals the joint between the cover and the casing, preventing the escape from the 45 interior of the container of any of the fluids that may be used. The closing of the cover also brings the pipes 17, when used, into operative relation with the bottles. The washing or sterilizing fluids may then be ad- 50 mitted by the operation of valves 8 and 19 with the fluid flowing into the header 6 and then through pipes 5 and conduits 4 to the nozzles 3, and also flowing through pipe 18 into the spraying devices. The nozzles project the cleansing fluid into intimate engagement with the interiors of the bottles, cleaning the same, and the fluid is also sprayed over the exteriors of the bottles, as shown 55 in Fig. 5, to similarly clean their outer surfaces. The bottles may then be removed as a whole, and the container is then ready to receive the next set of bottles. Bottles of another size being assembled in an appropriate container, the nozzles are re-spaced to 60 conform with the spacing of the necks of such bottles, members 10 being slid along the ledges 9 into proper position. When the members 10 are connected by linkage, as the lazy-tongs shown, movement of any one of the members in one set produces a simultaneous and proportionate movement of all of the other members in one set, whereby the proportionate spacing of the nozzles is maintained constant. Where calibrated bar 15 is employed, the members 10 may be readily 70 positioned by moving the same into coincidence with the appropriate calibration on the bar. If the bar also operates as a clamping member as shown, the screws 16 may be tightened to firmly clamp members 10 in 75 their adjusted position. The receptacle 26 and frame 27 with its contained bottles are then inverted and the frame supported on the members 10 with the bottles in operative relation to the nozzles as before, bar 30 and 80 flanges 33 being adjusted into engagement with the frame 27 as before explained. The washing or sterilizing fluid is then admitted, as heretofore pointed out, and the bottles subsequently removed. Thus, by having a 85 number of receptacles 26 and frames 27 of assorted sizes, it will be perceived that while one set of bottles is being cleansed, a second set of the same or different size may be assembled ready for insertion in the apparatus 90 immediately that the first set has become properly cleaned. Thereby, without any special skill, the articles to be cleaned can be readily assembled and positioned in proper relation to the fluid distributing ap- 100 paratus, and such apparatus may be kept in substantially constant use. By providing a plurality of pipes 7 leading from different sources of fluid, different fluids may be successively admitted to the distributing ap- 105 paratus to thoroughly wash and sterilize the bottles at one operation.

By reference to Figs. 4 and 6, it will be observed that the nozzles extended through each member 10 of one set of spacing devices form a row of nozzles within said member, which row is parallel to the row of nozzles within each of the other members 10 of the same set, so that when one member 10 is moved, all the rows of nozzles co-oper- 110 ating with the members 10 of said set are moved toward and from one another. It will also be observed, that the nozzles in each row are also individually movable toward and from one another in a direction 120 substantially at right angles to the direction in which said row of nozzles is moved, which is effected by movement of any member 10 of the second set in a direction substantially at right angles to the movement of the member 10 of the first-mentioned set. It will further be observed that when the nozzles are moved by the members 10 of one set, the members 10 of the other set act as guides for the said nozzles. Also it will be ob- 125 130

served that the nozzles have a definite spaced relation and in the present instance, the relation is such that four adjacent nozzles form the corners of a square, whose length is substantially equal to the width or diameter of the bottles or other articles at their widest part, and that when the nozzles are adjusted to receive bottles or other articles of different sizes, the four nozzles referred to when adjusted retain the same relation to a square of a different size.

While the invention has been described with considerable particularity, it is to be expressly understood that the same is not to be restricted to the construction illustrated on the drawings, as the same is capable of receiving a variety of mechanical forms, some of which will readily suggest themselves to those skilled in the art. Furthermore, certain features of the invention are capable of use without other features thereof. Therefore the limits of the invention are to be defined by the claims hereto appended.

25 What is claimed is:—

1. In a device of the character described, in combination, a plurality of nozzles individually movable in paths substantially at right angles to each other, said nozzles being arranged in rows substantially at right angles to one another, a movable device engaging the nozzles in one row, and a movable device engaging the nozzles in a row substantially at right angles to the first-mentioned row, whereby the nozzles in each row may be moved simultaneously in a direction transverse to the length of said row.

2. In a device of the character described, 40 in combination, a plurality of nozzles arranged to form the corners of a square and individually movable in different directions substantially at right angles to each other, means for moving said nozzles individually 45 to form the corners of squares of different areas whose sides are substantially equal in length to the greatest width or diameter of the articles to be placed over the said nozzles, and enable the same nozzles to be used with 50 the same number of articles of different diameters.

3. In a device of the character described,

the combination of a container, distributing means for a washing or sterilizing fluid therein, said means comprising a plurality of movable nozzles, sets of movable members arranged transversely to each other and engaging said nozzles to move the same in different directions substantially at right angles to each other and to maintain the 60 same in spaced relationship, and means for simultaneously adjusting the members of either of said sets independently of those of the other to simultaneously and proportionately vary the spacing of said nozzles.

4. In a device of the character described, the combination of a container, a header, a plurality of pipes leading from said header, a plurality of nozzles in said container flexibly connected with said pipes, 70 and means adjustable in directions substantially at right angles to each other for maintaining said nozzles in predetermined spaced relationship.

5. In a device of the character described, 75 in combination, a set of substantially parallel longitudinally slotted bars, a second set of substantially parallel longitudinally slotted bars arranged transversely with relation to the first-mentioned set with the slots of the 80 bars in one set crossing the slots in the bars of the other set, a plurality of individually movable nozzles extended through the slots in the bars of both sets, and means for simultaneously moving the bars in one set with 85 relation to the bars of the other set to effect movement of said nozzles.

6. In a device of the character described, 90 in combination, a plurality of nozzles individually movable, sets of adjustable parallel 95 simultaneously movable members arranged substantially at right angles to each other, each nozzle being engaged by one member of each set and the members coöperating with said nozzles to effect movement of the nozzles in one direction by moving one set of members and to effect movement of the said nozzles in a direction substantially at right angles to the first-mentioned direction by moving the other set of said members.

100 In testimony whereof I have signed this specification.

FREDERICK S. BURNHAM.
